UNITED STATES PATENT OFFICE.

EDWARD ERMOLD, OF NEW YORK, N. Y.

ENVELOP-MACHINE.

No. 807,369.

Specification of Letters Patent.

Patented Dec. 12, 1905.

Application filed April 7, 1905. Serial No. 254,364.

To all whom it may concern:

Be it known that I, EDWARD ERMOLD, a citizen of the United States, residing in New York, borough of Manhattan, in the State of New York, have invented certain new and useful Improvements in Envelop-Machines, of which the following is a specification.

It is well known that when transferring the paste from the paste-roller of the envelop-machines to the flaps of envelop-blanks a number of envelopes receive more than the required quantity of the adhesive material when the elevator on which the pile of blanks is supported is raised again after placing a new pile of envelop-blanks thereon, as during the time required for lowering the elevator and placing a new pile thereon the paste-roller continues its reciprocating motion and takes up a too large quantity of paste without being able to transfer the same in the regular manner to the envelop-blanks. When the elevator is returned with a pile of blanks, the blanks on top of the pile receive then an extra quantity of paste from the roller. This objectionable transfer of the surplus paste to the blanks continues until the quantity of paste on the paste-roller is diminished and the paste-roller restored to its normal condition, so that the transfer of the paste to the flaps can then again take place in the regular manner. The extra quantity of paste transferred to the flaps necessitates the rejection of a number of the envelopes as defective.

The object of this invention is to improve the envelop-machine in such a manner that the movement of the paste-transferring roller is automatically interrupted when the elevator carrying the pile of envelop-blanks is raised to such an extent that nearly all the blanks are fed to the pickers, so that no reciprocating motion is imparted to the paste-transferring roller while the elevator is lowered for receiving a new pile of blanks, the elevator on being moved reestablishing automatically the regular working of the paste-roller until the motion of the paste-roller is again automatically interrupted, when the pile of envelop-blanks is again exhausted; and for this purpose the invention consists of an envelop-machine in which the paste-roller is combined with means for automatically interrupting the reciprocating motion of the same when the pile of blanks fed to the pickers becomes gradually exhausted, so that the taking up of paste by the roller is temporarily interrupted.

The invention consists, further, of means

for automatically starting the motion of the paste-transferring roller at the proper time after a new pile of blanks is supplied to the elevator, and the invention consists, lastly, of certain additional features and details of construction by which these objects are carried out, which details will be fully described hereinafter and finally pointed out in the claims.

In the accompanying drawings, Figure 1 is a front elevation of an envelop-machine, partly in section, with my improved attachment for automatically interrupting the motion of the paste-roller when the pile of blanks is gradually exhausted and starting the paste-roller when a new pile is placed on the elevator. Fig. 2 is a side elevation, partly in section, on line 2 2, Fig. 1, of the mechanism for interrupting and starting the motion of the paste-transferring roller. Fig. 2^a is a detail of a portion of the mechanism for transmitting motion to the knocker-pin. Fig. 3 is also a detail, partly in vertical transverse section on line 3 3, Fig. 1, of the stop mechanism for the paste-roller. Fig. 4 is a detail front view of the mechanism for interrupting the reciprocating motion of the paste-roller drawn on a larger scale. Fig. 5 is a plan view of Fig. 4. Fig. 6 is a vertical longitudinal section on line 6 6, Fig. 5. Fig. 7 is a detail front elevation of the latch for locking the stop mechanism of the paste-roller. Fig. 8 is a detail plan view of the actuating-lever of the stop mechanism for the paste-roller. Fig. 9 is a detail vertical transverse section on line 9 9, Fig. 4, of the clutch mechanism connected with the motion-transmitting mechanism of the paste-roller for interrupting the motion of the same; and Fig. 10 is a side elevation, partly in section, through the knocker-pin of the stop mechanism for the paste-roller.

Similar letters of reference indicate corresponding parts.

Referring to the drawings, A represents the supporting-frame of my improved envelop-machine, and A' the table supported thereon. On the table A' is supported the upper frame A², on which the pickers P, folders, and other operative parts of the envelop-machine are supported. To the upper frame A² are attached transverse yokes A³, which support two parallel rods a, on which are guided the sleeves a', from which the reciprocating paste-roller B is suspended. The shaft of the paste-roller B is supported in hook-shaped bearings a², which are suspended from the sleeves a'. The paste-roller B takes up the paste by con-

tact with feed-rolls b , which are located in a paste-receptacle B' , that is supported on the upper frame A' , the rolls b and the paste-receptacle being of the usual well-known construction. Below the reciprocating paste-roller B is arranged in an opening of the table A' the platform E' of the elevator E by which the envelop-blanks are fed to the pickers, the elevator being raised or lowered by the well-known rack-and-pinion mechanism. The shaft of the pinion is provided at its front end with a hand-wheel for raising or lowering the elevator by hand whenever necessary.

Reciprocating motion is imparted to the paste-roller B by a motion-transmitting mechanism from a cam-shaft S' , which is located in bearings at the lower part of the main frame A and rotated by a gear-wheel transmission $g' g'$ from a driving-shaft S in the usual manner. On the gear-wheel g' is located a cam g^2 , the cam-groove of which engages an antifriction-roller g^3 , which is applied to a vertically-reciprocating rod r , that is guided in a keeper r' , provided below the roller g^3 with a forked end r^2 , so as to move along the cam-shaft S' . To the vertically-reciprocating rod r is pivoted the lower end of a connecting-rod r^3 , the upper end of which is adjustably pivoted to the lower arm of a fulcrumed elbow-lever r^4 , which is fulcrumed to a bracket r^5 , that is attached to the main frame A . The upper arm of the elbow-lever r^4 is provided with a toothed segment r^6 , that engages a pinion r^7 , the shaft r^8 of which is supported in hanger-bearings r^8 , said pinion-shaft being mounted at both ends with reciprocating lever-arms r^{10} , which are again connected at their upper ends by pivoted connecting-rods r^{11} with lugs r^{12} on the sliding sleeves a' , from which the paste-roller B is suspended. The cam-groove g^2 is so shaped that by the intermediate mechanism described the paste-roller B is reciprocated on its guide-rods a , said motion being timed in such a manner that the paste is imparted to the pickers P and transferred from the same to the flaps of the envelop-blanks before they are folded by the folding mechanism. The mechanism by which reciprocating motion is imparted to the paste-roller B is well known and forms no part of the present invention.

The novel feature consists in the mechanism by which the motion of the paste-roller B is temporarily interrupted and the same arrested at the opposite end of its stroke, so as to prevent the transfer of the paste from the paste-transferring roll b to the pickers P when a new pile of envelop-blanks is placed on the elevator-platform E' . For this purpose the arms of the elbow-lever r^4 are not made in one piece, but separated from each other, the hub of the lower arm being placed on the hub of the upper arm, as shown in Fig. 9, so as to be locked together or released from each other by a clutch mechanism. The upper arm of the elbow-lever r^4 is supported on

a shaft d , which is supported in a block d' on the bracket r^5 . The hub d^2 of the upper arm of the elbow-lever r^4 is placed loosely on the shaft d and held against the front shoulder of a middle enlarged portion d^5 of the shaft by a head d^3 at the front end of the shaft, while the rear end is attached by a screw-nut d^4 to the stationary block d' . The block d' abuts against the rear shoulder of the intermediate enlarged portion d^5 . The hub d^6 of the lower arm of the elbow-lever r^4 is provided with three holes d^7 , which are adapted to be engaged by a corresponding number of clutch-pins d^8 , that are attached to the circumferential flange of a clutch d^9 , that is placed slidably on the enlarged portion d^5 of the shaft d . The clutch d^9 is held against the hub of the upper arm of the elbow-lever r^4 by means of spring-actuated pins d^{10} , that are guided in holes of the stationary block d' . The clutch d^9 is provided with a circumferential groove e , that is engaged by inwardly-projecting pins e' of the ring-shaped portion e^2 of a clutch-operating lever D , which is fulcrumed to a supporting-bracket e^3 , attached to the frame A . The fulcrum $d^{\times}$ of a clutch-operating lever D is carried by a keeper e^4 , which turns in the bracket e^3 , so that the lever D can be oscillated in a horizontal as well as in a vertical direction. The outer end of the clutch-operating lever D is connected by a helical spring e^5 with a suitable support e^6 on the frame A , so as to be drawn in downward direction in the slot of the bracket e^3 . The outer end of the lever D is further provided with a rearwardly-projecting lug e^7 , that is intermittently placed in the path of an oscillating rocker-pin f , which is guided in a socket f' , the rocker-pin being actuated by a helical spring f^2 , which is placed on the shank of the rocker-pin and interposed between the head of the pin and the upper end of the socket, as shown clearly in Fig. 10. The socket f' is supported on the upper arm of a rocking elbow-lever f^3 , which is fulcrumed to the frame A , while the lower arm of the elbow-lever f^3 is connected by a rod f^4 , having a forked lower end f^5 , as shown in Fig. 2^a, with a cam f^6 on the cam-shaft S' , the cam f^6 acting on a roller f^7 on the forked lower end of the rod f^4 , so that the rocker-pin f is intermittently oscillated by the cam f^6 and the intermediate mechanism for engaging the lug e^7 at the outer end of the clutch-lever D when the same is placed in the path of the rocker-pin f .

To the upper part of the bracket r^5 is applied a short arm h , which extends at right angles to the bracket in forward direction and which serves to engage a recessed keeper h' , that is attached to the flange of the laterally-slidable clutch d^9 , so as to interlock with the same when the clutch d^9 is shifted against the pressure of the pins d^{10} and produce thereby the locking of the clutch-lever D in position, so as to be acted upon by the rocker-

pin. To the opposite or inner end of the clutch-lever D, adjacent to the ring-shaped portion of the same, is attached a curved horizontal arm g, which is provided with a recess g' adjacent the lever D and which extends backwardly through an opening in the bracket r⁵, as shown in Figs. 4 and 5. To the bracket r⁵ is fulcrumed a spring-actuated latch g², which drops into the recess g' when the clutch-lever D is moved toward the bracket, so that the arm g is passed in backward direction through the opening in the bracket from the position shown in full lines in Fig. 8 to that shown in dotted lines in the same figure, so that the latch engages the recess g' and locks thereby the arm g and the clutch-lever D alongside of the bracket r⁵, as shown in Figs. 6 and 7. The latch g² is provided with a downwardly-extending nose-piece g³, which extends at an obtuse angle to the shank of the latch and which in the locked position of the latch is placed in the path of the inclined face on the curved lower end of an arm E², that is attached to the under side of the elevator-platform E', so that on the raising and lowering of the elevator and its platform the lower end of the arm forms contact with the nose g³ of the latch g², presses on the same, and moves the latch on its fulcrum against the tension of its spring, so as to release it from the recessed arm g and permit thereby the return of the clutch-lever D into the position shown in full lines in Figs. 5 and 8. While the clutch-lever D is placed in locked position, the sliding clutch d⁹ is moved on the enlarged portion d² of the shaft d in backward direction against the tension of the pins d¹⁰, so as to withdraw the clutch-pins d⁸ from the holes d⁷ in the hub of the lower arm of the elbow-lever r⁴, so that no oscillating motion can be transmitted to the upper arm of the elbow-lever r⁴. The reciprocating motion of the paste-roller is thereby instantly interrupted and no paste transmitted to the face of the pickers. As soon as the latch is released from interlocking action with the recessed arm of the clutch-lever D the latter is returned, together with the clutch d⁹, into normal position, so that the clutch-pins on the hub of the upper arm of the elbow-lever r⁴ interlock with the holes in the hub of the lower arm and impart reciprocating motion to the paste-roller B, so that paste is again transmitted by the same to the face of the pickers.

The arm E² is attached to the under side of the platform E' in such a manner as to permit its proper adjustment relatively to the latch to be operated thereby. It is provided at its middle portion with a curved bracket E³, to which is pivoted a heel i, the shank of which moves between two pins r⁶, one at each side of the same. The lower straight part of the heel i is placed in the path of the inner end of the lever D when the same is in its normal position and clears the same by swinging side-

wise on its pivot when the platform E' and arm E² are moved in upward direction, but producing the engagement of the heel i with the end of the lever D by the downward motion of the elevator-platform, so that the outer end of the clutch-lever is raised and placed into the path of the rocker-pin f, so that the side of the latter engages the same in the manner shown in Fig. 6, and horizontal motion is thereby imparted to the clutch-lever 70 and the clutch d⁹ shifted out of operative position. Said lever is then locked by the latch g², so that the attendant can place a new pile of envelop-blanks on the elevator-platform E', while the motion of the paste-roller B is interrupted. By then raising the elevator the curved lower end of the arm E² engages the nose of the latch g² and releases it from the arm g on the clutch-lever D, so that the latter is instantly returned into its normal position, so as to cause the locking together of the arms of the elbow-lever r⁴, and thereby the instant resumption of the motion of the paste-roller and the transfer of paste to the envelop-blanks of the new pile. The upward motion of the elevator produces, by the releasing of the clutch-lever D by the lower end of the arm E², the automatic interruption of the reciprocating motion of the paste-roller, while the automatic dropping of the elevator produces the engagement of the heel i on the arm E² with the lever D, the relocking of the clutch-lever, and thereby the restarting of the reciprocating motion of the paste-roller. When the pile of blanks on the elevator-platform is sufficiently reduced in size so that a new pile has to be supplied, the elevator is automatically dropped in the usual manner and produces, by the action of the heel i on the clutch-lever D, the locking of the clutch-lever D and the interruption of the reciprocating motion of the paste-roller until a new pile of blanks is placed on the elevator and the same raised in position, so that the uppermost blank is below the pickers. During the upward motion of the elevator the lower end of the arm E² releases the latch and produces the instant return of the clutch-lever and clutch into engagement with the operating mechanism of the paste-roller, so that the latter resumes its motion 100 and transfers paste to the pickers, the setting of the clutch mechanism by which the motion of the paste-roller is interrupted or established being accomplished by the automatic lowering and raising of the elevator and the action of the heel and curved arm on the elevator-platform, on the clutch-lever, and the clutch mechanism operated thereby.

The advantage of my improved attachment for envelop-machines is that the reciprocating motion of the paste-roller is automatically and intermittently interrupted when the same is not required for transmitting paste from the paste-receptacle to the pickers and that its reciprocating motion is reestablished when a 125

new pile of blanks is placed on the elevator-platform and the regular motion of the envelop-machine re-established, whereby the transfer of surplus paste to the face of the 5 pickers, the overgumming of the envelop-flaps, and the waste of envelopes in consequence thereof is obviated and the uniform gumming of the flaps of the blanks, and thereby the more efficient working of the paste-supply 10 mechanism of the envelop-machine, obtained.

Having thus described my invention, I claim as new and desire to secure by Letters Patent—

1. In an envelop-machine, the combination, with a paste-roller and means for imparting 15 reciprocating motion to the same, of a mechanism for interrupting the motion of the roller-operating mechanism, and an elevator-platform provided with means for actuating said interrupting mechanism during the descending 20 and ascending motion of the platform.

2. In an envelop-machine, the combination, with a paste-roller and mechanism for reciprocating the same, of a clutch mechanism arranged for interrupting or restoring the motion 25 of the reciprocating mechanism, and an elevator-platform provided with means for releasing the clutch from or relocking the same with said reciprocating mechanism.

3. In an envelop-machine, the combination, 30 with a paste-roller and mechanism for imparting reciprocating motion to the same, of a clutch mechanism adapted to interrupt or re-establish the motion of the reciprocating mechanism, an oscillating lever connected with said 35 clutch mechanism, a rocker-pin adapted to engage one end of said lever, means for oscillating said rocker-pin, and an elevator-platform provided with means for acting on the opposite end of the lever.

4. In an envelop-machine, the combination, with a paste-roller and means for imparting reciprocating motion to the same, of a clutch mechanism adapted to interrupt or restore the motion of said reciprocating mechanism, 45 a lever connected with said clutch, said lever being capable of a horizontally and a vertically rocking motion, an oscillating rocker-pin adapted to engage one end of said lever, a locking device for locking the opposite end 50 of said lever after it has been shifted by said rocker-pin, and an elevator-platform provided with means for engaging the opposite end of said rocking-lever and with means for releasing the locking device and clutch-lever.

5. In an envelop-machine, the combination, with a paste-roller and means for imparting reciprocating motion to the same, of a clutch mechanism interposed in said reciprocating mechanism, a lever connected with said clutch 60 mechanism and adapted to be rocked horizontally and vertically, an oscillating rocker-pin adapted to engage one end of said clutch-lever, a locking device adapted to lock the opposite end of the clutch-lever, a vertically-recipro- 65 cating elevator-platform, an arm attached to

the under side of said platform and adapted to release the locking device from the clutch-lever, and a heel pivoted to said arm and adapted to engage the clutch-lever for placing it in the path of the rocker-pin for locking 70 the clutch-lever.

6. In an envelop-machine, the combination, with a paste-roller and mechanism for reciprocating the same, of a clutch interposed in said reciprocating mechanism, a clutch-lever 75 connected with said clutch, an oscillating rocker-pin adapted to engage one end of said clutch-lever, a locking-latch adapted to engage the opposite end of said lever for locking the same, a vertically-reciprocating elevator-platform, a downwardly-extending arm applied to the under side of said platform, a heel pivoted to said arm parallel with the same and adapted to engage the inner end of said clutch-lever so as to place in the path of 85 the rocker-pin and produce the locking of the clutch-lever and of the clutch out of mesh with the mechanism for transmitting reciprocating motion to the paste-roller.

7. In an envelop-machine, the combination, 90 with a paste-roller and mechanism for imparting reciprocating motion to the same, of a clutch interposed in said reciprocating mechanism and composed of a movable and spring-actuated member, a stationary member, and 95 interlocking means between said members, a clutch-lever connected with the movable clutch member, an oscillating rocker-pin adapted to engage the outer end of said clutch-lever, means for imparting intermittent oscillating 100 motion to said rocker-pin, a vertically-reciprocating elevator-platform, a pivoted heel supported below said platform for engaging the inner end of the clutch-lever and shifting its outer end into engagement with the rocker- 105 pin, a locking-arm on said clutch-lever, and a pivoted and spring-actuated latch for locking said arm and clutch-lever and holding the movable clutch member out of mesh with the stationary member, for interrupting the motion 110 of the reciprocating mechanism of the paste-roller.

8. In an envelop-machine, the combination, with a paste-roller and mechanism for imparting reciprocating motion to the same, of a 115 clutch interposed in said reciprocating mechanism, and composed of a movable and spring-actuated member, a stationary member, and locking-pins between said members, a rocking clutch-lever connected with said movable 120 clutch member, an oscillating rocker-pin adapted to engage the outer end of said clutch-lever, means for intermittently actuating said rocker-pin, a locking-latch adapted to engage and lock the inner end of the clutch-lever, a 125 vertically-reciprocating elevator-platform and a curved arm attached to the under side of said platform, and located in the plane of the locking-latch, said arm engaging the latch during the upward motion of the platform for 130

releasing the clutch-lever, returning the clutch members into mesh with each other and resuming the reciprocating motion of the paste-roller.

- 5 9. In an envelop-machine, the combination, with a paste-roller and mechanism for imparting reciprocating motion to the same, of a clutch interposed in said reciprocating mechanism, and composed of a movable and spring-
10 actuated member, a stationary member, locking means between said members and a device for locking the movable member after it is withdrawn from the stationary member, an oscillating rocker-pin adapted to engage the
15 outer end of said clutch-lever, means for intermittently actuating said rocker-pin, a locking device adapted to lock the inner end of the

clutch-lever, a vertically-reciprocating elevator-platform and means supported at the under side of said platform for actuating the 20 movable clutch member and locking the same by its locking device and simultaneously locking the clutch-lever, and means for releasing the locking-lever and movable clutch member for actuating the reciprocating mechanism of 25 the paste-roller.

In testimony that I claim the foregoing as my invention I have signed my name in presence of two subscribing witnesses.

EDWARD ERMOLD.
